(57) **CLAIM**

The ornamental design for a free standing animal feeding stand, as shown and described.

DESCRIPTION

FIG. 1 is an overall perspective view of a free standing animal feeding stand showing any new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof; and,

FIG. 7 is a bottom plan view thereof.

The broken line showing of the animal feeding bucket is for illustrative environmental purposes only and forms no part of the claimed design.
